UNITED STATES PATENT OFFICE.

ARTHUR L. COLTON, OF MILWAUKEE, WISCONSIN.

LETTER-FILE.

SPECIFICATION forming part of Letters Patent No. 331,185, dated November 24, 1885.

Application filed February 24, 1885. Serial No. 156,830. (No model.)

To all whom it may concern:

Be it known that I, ARTHUR L. COLTON, of Milwaukee, in the county of Milwaukee, and in the State of Wisconsin, have invented certain new and useful Improvements in Letter-Files; and I do hereby declare that the following is a full, clear, and exact description thereof.

My invention relates to letter-files; and it consists in certain peculiarities of construction, all as will be more fully set forth hereinafter.

In the drawings, Figure 1 is a perspective view of my improved file in its case, with the clamping device down. Fig. 2 is a longitudinal central vertical section of the same with the clamping device raised. Fig. 3 is a plan view of part of the back of the file-case with the top plate of the housing broken away, and showing the clamping-device attachments in section on the line $y y$ of Fig. 2. Fig. 4 is a vertical section through the back of the case on the line $x x$ of Fig. 3, and Figs. 5 and 6 are details.

A is the case or box of my file, and this is centrally cut away at the back to receive the housing B, consisting of an inner or front plate, b, which is extended back over the top of the cut-away portion of the case, forming the top plate, b', and brought down a short distance, as at b², on the back of the case. The said plate b b' is provided with two slots, b³ b³, and the central part of the top plate, b', between these slots is supported by means of the rear extension, b², of said plate. Within the cut-away portion of the back of the case, protected by the housing B, are two plates, C C, one on each side, which have right-angled flanges c c, extending from the bottom to nearly the top of said plates, and extending inward—that is, toward each other—as shown in Fig. 3, to serve as guides for the rear part, d, of the slide D, as hereinafter explained. Above these flanges c the plates C are bent around to form bearings c' for the journals e of the operating-levers E of the clamping device, and while the flanges c are set forward far enough within the cut-away portion of the back of the case so that the rear plate, d, of the slide may be flush with the rear of said case, the rear part of the bearings c' will extend as far back as the space will permit, (or

practically as far back as the said plate d,) in order to give all possible leverage to the levers E of the clamping device. The bottom plate 55 of the slide D is cut out at each side, as shown in Fig. 3, to receive the guides c c, and in front of these points the said plate is provided with two perforated lugs, d² d², to receive the double-crank arm D', the cranked ends of 6c which, d' d', are connected to the levers E E at a point forward in vertical line (when the levers E are raised) of the journals e, to form links, and, being forward of the center of said levers, will enable the clamping device 65 to be more easily pulled down when necessary. The housing B is completed by a rear plate B', having a vertical slot, b⁴, which admits the shank of the screw-bolt D², (which screws into the slot D,) by means of which the slide is 70 moved up or down to operate the clamping device, and which screw may be tightened at any point, so as to hold the plate B', plate d, and guides c c all firmly together, and hence to keep the slide D and the clamping device 75 operated thereby at any desired position, either up or down, at will.

I will next describe the construction of my clamping device. My levers E E are bent, as shown, at a right angle twice, each having the 80 short arms pivoted, as described, by the journals e e, to the bearings c' c' of the plates C C, within the housing B, and extending forward through the described slots b³ b³, and then bent outward parallel with the back of the case 85 toward and to the sides of the said case, and terminating in the long arms E' E', bent so as to be parallel with the sides of the case, as well as with the short arms; and the front ends of these long arms are each provided with a hole, 90 e', to receive the ends of the clamping device proper, as hereinafter explained.

I preferably provide my levers with two braces—one, E², between the short arms, and one, E³, between the long arms E' E', near the 95 front ends of said arms—and these braces may be attached to the lever-arms in any suitable way, as by rivets, solder, or otherwise. The clamping piece consists, primarily, of the rod F and oval frames G G, constructed preferably as follows: The rod F at one end is bent around near the center of the outer side of one of the oval frames G, and then outward through the hole e' in the end of the long arm 100

E' of the lever on that side, and then back under the frame G and over again, its end being bent down snugly against the frame, all as shown in the detail view, Fig. 5, forming a 5 triple loop, the central strand of which is the longest, and which forms the pivotal connection with the end of the lever-arm E'. The other end of the rod F is secured in precisely the same way. The oval frames G G are not 10 continuous, but have each a pair of stems, g g, from their inner sides, extending toward each other, each pair of stems straddling the rod F and meeting in the center, the said stems and rods being united together by any 15 suitable means, such as solder, or by being flattened and provided with rivets, or by binding a wire or other covering around them, as most convenient or ornamental. The ovals are preferably so disposed that the ends G' G' 20 of said frames are at a greater distance from the rod F than the ends G² G², and hence when the clamping-frame is raised the ends G' G' will maintain the lowest position, and therefore will first strike the letter-file, when 25 the clamping-frame is again lowered near the rear of the case, and so will automatically be in proper position always to press down on the contents of the file.

H represents the letter-file proper, formed 30 of a number of sheets of paper or other suitable material, and suitably indexed along their front edges, as by alphabetical arrangement of letters or other devices, to indicate the nature of the letters, &c., to be deposited 35 between said sheets. Near the rear edges of said sheets they are perforated with two holes, h h, which may be round or oblong, and which may be re-enforced or strengthened in any suitable manner, (as by cloth pasted on the paper 40 sheets before perforating them, as indicated by dotted lines h' h' in Fig. 1.)

The letter-file H is secured to the case A in the following manner: The inner side of the back of the case is provided with two vertical 45 square-edged grooves, a a, which are each fitted with two headed bolts or screws, a' a', projecting out from said grooves, so as to leave a space between the head of each screw and the groove equal to the thickness of the plates 50 I I, which are each provided with two key-hole slots i i, and these plates I may be made either of cast metal, as in Figs. 1 to 4, or may be stamped out of sheet-tin or other sheet metal, as in Fig. 6, as preferred. In the former case they would be cast with a perforated lug, i², at the top, to receive the split ring J and hook K; and in the latter instance, instead of a cast lug, a bit of the metal would be bent over in front with its end passed into a hole and 55 clinched on the reverse side, the said metal piece forming a loop, i², to hold the said ring J and hook K. From the base of each plate I a wire, I', extends out at right angles thereto, and then is itself bent at a right angle parallel with 60 the plate I, and terminating in a hook or eye, i', to receive the ring J after the sheets of the

file H have been adjusted on the wires I', as shown in Fig. 4, and then the plates I I are slipped to place in the grooves a a, and secured therein by means of the key-hole slots i and 70 screws a', and for greater security the hooks K are then fastened under the upper screws, a', in each groove, thus guarding against accidental displacement or removal of the plates I. To aid in releasing these hooks K (as well as 75 fastening them) when the file is nearly full, shallow rounded grooves a² a² are cut, communicating with the grooves a a on each side at a height corresponding about with the shanks of the hooks, which affords a ready means of 80 communication (as by the finger or a pencil, &c.) with the said hooks K. I may, if desire stamp the part I' out of the same body of sheet metal with the plate I, instead of soldering or riveting a separate wire or piece thereto, as 85 shown, bending the part I' into the required form.

The operation of my device will be readily understood from the foregoing description of its construction.

A great advantage of my described clamping-frame consists in the two independent oval frames G G, as thereby commercial note and postal-cards may be built up in independent piles under each frame G, and always be kept 95 clamped down thereby, while letter-sheets of full size would of course extend under both frames G G, and thereby my present file is adapted to properly contain a larger amount of matter, always evenly pressed down by reason of said peculiar clamping device, than 100 would be the case if it were not used.

If at any time I wish to transfer my file H and its contents to another case or place of deposit, I can do so by releasing the hooks K K, 105 raising the clamping-frame and taking the file H and its plates and rods I I', &c., out bodily, and placing a similar but empty file H I I' J with the case A.

If desired, in place of the crank-rod D', extending between the lugs d d' of the slide D, I may utilize merely the crank ends d' d' of said rod as links, connecting to said lugs d d' 110 of the lever-arms E.

Having thus described my invention, what 115 I claim as new, and desire to secure by Letters Patent, is—

1. In a letter-file, the combination of a case and a series of loose sheets secured thereto with a clamping device connected by links and 120 pivots to a slide having vertical play within the back of the case, as set forth.

2. In a letter-file, the combination, with the case and a series of loose sheets secured thereto, of a clamping device consisting of lever-arms connected by links and pivots to a slide 125 having vertical play within the back of the case, and having pivoted to said lever-arms two independent oval frames adapted to exert pressure independently on the upper and lower portions of said sheets, as set forth.

3. In a letter-file, the combination of the

case having vertical grooves on the inner side of the back of said case, and a series of loose sheets held together by means of rods passing through perforations near the rear of said 5 sheets, said rods being secured to plates adapted to slide within the grooves in the case back, and fastening devices whereby said sheets, with their rods and plates, may be secured to the case or removed bodily therefrom, as set 10 forth.

4. In a letter-file, the combination of the case A, centrally cut out at the back, and having loose sheets H, mounted on rods passing through perforations in said sheets, and connected to plates secured to said case, with the housing B, consisting of an inner or front plate extended back over the cut-away portion of the case, forming a top plate, b', and provided with slots b³ through the upper part 20 of the front plate and through the top plate, and a rear plate, B', having central vertical slot b⁴, vertical guide-plates C C, one on each side of the cut-away portion of the case-back, and provided with right-angled guiding-flanges c c, slide D, with rear plate, d, adapted to engage with the flanges c, screw-bolt D², the shank of which has vertical motion in the slot b⁴, and which screws into the plate d, and a clamping device having lever-arms which 25 extend through the slots b³, and are pivoted to projections on the guide-plates C and slide D, and which are adapted to be raised and lowered by the slide D, and to release or press down on the loose sheets H, and be secured in 30 either position by the screw-bolt D², substantially as set forth.

5. In a letter-file, the combination of the case A, provided with the vertical grooves a a in the inner side of the case-back, and retaining-bolts a' a', projecting from said grooves a, vertical plates I, having loops or lugs i² on top and fitting within said grooves, and having key-hole slots i for engagement with said retaining-bolts, and rods I', connected to said 45 plates I at the base, and terminating at top with hooks or eyes i', loose sheets H, having perforations h, whereby they are strung upon the rods I', and rings J, connecting the hooks or eyes i' with loops or lugs on the upper end 50 of the plates I, substantially as set forth.

6. In a letter-file, the combination of the case A, provided with the vertical grooves a a in the inner side of the case-back, and horizontal grooves a² a², communicating with the grooves 55 a a, and retaining-bolts a' a', projecting from said grooves a, vertical plates I, having loops or lugs i² on top and fitting within said grooves, and having key-hole slots i, for engagement with said retaining-bolts, and rods I', connected to said plates I at the base, and

terminating at the top with hooks or eyes i', loose sheets H, having perforations h, whereby they are strung upon the rods I', rings J, connecting the hooks or eyes i' with the loops or lugs i², and hooks K depending from the loops 65 or lugs i² and adapted to lock the plates I, after the same have been adjusted by means of the bolts a' and slots i, by interposing the free ends of said hooks around the shanks of the upper bolts, a', between the inner surface 70 of the heads of said bolts and the outer surface of said plates I, substantially as set forth.

7. In a letter-file, the combination of the case A, centrally cut out at the back, and having loose sheets H, mounted on rods passing through perforations in said sheets, and connected to plates secured to said case, with the housing B, consisting of an inner or front plate extended back over the cut-away portion of the case, forming a top plate, b', and provided with 80 slots b³ through the upper part of the front plate and through the top plate, and a rear plate B', having central vertical slot b⁴, vertical guide-plates C C, one on each side of the cut-away portion of the case-back, and provided with right-angled guiding-flanges c c, and bearings c' c' above said flanges, slide D, cut out at each side to receive the flanges c c, and having a rear plate, d, the ends of which have vertical movement between the plate B' 90 and the rear surface of the flanges c c, and provided with perforated lugs d² d², screw-bolt D², the shank of which has vertical motion in the slot b⁴, and which screws into the plate d, a clamping device having lever-arms E E, extending through the slots b³, and having journal ends e e, pivoted in the bearings c' c', and double crank-arm D', extending across the length of the slide D and through the lugs d² d², and having cranked ends d' d', connected to 95 the lever-arms E E at a point forward of the pivotal points of the journals e, substantially as and for the purposes set forth.

8. In a letter-file, the combination of the case A and sheets H, attached thereto, with a clamping device consisting of the lever-arms E E', rod F, and oval frames G G, secured to said rod F near the centers of the ovals, but with the greater length of said ovals near the rear of the file-case when closed, and near the bottom of said case when the clamping device is raised, as set forth.

In testimony that I claim the foregoing I have hereunto set my hand, at Milwaukee, in the county of Milwaukee and State of Wisconsin, in the presence of two witnesses.

ARTHUR L. COLTON.
